UNITED STATES PATENT OFFICE.

CHARLES J. ABELN, OF ST. LOUIS, MISSOURI.

SHOW CASE.

Application filed April 28, 1924. Serial No. 709,384.

This invention relates to show cases, and more particularly to show cases intended for displaying cigars and the like for sale.

In selling cigars, it is the customary practice to display the goods in a show case of attractive appearance in such a way that the prospective purchaser may look over an assortment of different brands preparatory to selecting the kind he wishes to purchase. When the selection has been made, the sale is usually made simply by opening the case so that the purchaser may help himself to as many of the articles as he desires. The sale is thus made directly from the show case. It is desirable, therefore, to provide a show case which will not only be capable of displaying to advantage a variety of different brands of the article, but which is conveniently arranged so that it may be opened to permit the purchaser to make his own selection and to actually remove the articles from the show case himself. In making the sale the attendant usually takes his place in a convenient position behind the case but in which he faces the customer directly and in an effective position for conversation or sales talk. It is, therefore, also desirable to have the show case constructed so that the attendant standing behind the case may manipulate the doors so as to open the same for the convenience of the customer.

One of the objects of this invention, therefore, is to provide a show case which will not only be capable of displaying to advantage a variety of articles, but which is conveniently arranged for opening and closing by an attendant in the rear thereof.

Another object is to provide such a case in which the attendant in the rear of the case may not only manipulate the doors, but may himself remove articles from the case from his position behind it.

Another object is to provide such a case having door manipulating devices of novel construction and arrangement.

Further objects will appear from the detail description taken in connection with the accompanying drawing, in which:

Figure 1 is a perspective view illustrating a show case embodying this invention;

Figure 2 is a transverse section of Figure 1;

Fig. 3 is an enlarged fragmentary perspective view showing the handle and its attaching means.

Fig. 4 is an enlarged fragmentary end view showing a cigar box mounted on the support.

Referring to the accompanying drawing, the show case here illustrated comprises a base or sub-structure 1 suitably designed to stand on the floor and having integrally constructed therewith a super-structure 2 which forms the show case proper. The part 2 is provided with a front sloping upwardly 60 to the rear and terminating at the upper part 65 thereof adjacent a narrow top 3.

The front is formed by a pair of horizontally movable doors 4 having transparent panels 5 and mounted as already stated to slope upwardly to the rear. The doors 4 may be mounted to slide or roll on suitable rails 6 at the top and bottom of the door opening and adapted to engage grooves in the upper and lower edges of the doors. 70 These doors are mounted to slide past one another so that either one may be moved aside to open the case. Along the abutting faces of the inner rails 7 of both doors, suitable sealing strips 8 may be provided to seal 75 the case against the entrance of dust when the doors are closed.

Fixed to the rear side of the upper rail 9 of each door and substantially at the middle thereof is a handle 10. This handle is provided with a shank bent at its inner end to provide an angular extension 11 which has riveted, welded or otherwise fastened thereto a cross member 12 adapted for attachment to the door 4. In order to save space the member 12 may be let into the surface of the rail 9 and is fastened thereto by screws 13 or other suitable means. This construction provides a rigid handle rigidly and securely attached to the door for moving the same. The rear wall 14 of the show case is provided with horizontal slots 15 through which the handles 10 project and in which these handles may move for operating the doors. The handles project through the slots 14 to the rear 100 of the casing and are positioned one above the other as illustrated in Figure 2 so that they may be easily grasped by the attendant and also that they may freely pass one another as the doors pass one another in their movement.

Within the case a series of shelves 16 may be provided which are arranged in tiers as illustrated in Figure 2. These shelves divide the case into an upper display com- 110

partment 17 and a lower compartment 18 which may be used for storage of extra stocks of goods. One of these shelves may be provided with an opening 19 beneath which is removably mounted a water pan 20 which serves to keep the atmosphere of the display compartment moist for the preservation of such goods as cigars which may be put on display. The lower shelf 16 10 may be provided with a similar opening closed by a cover or cap 21. Such an opening is convenient for the purpose of cleaning the case. The accumulated dust and dirt on the shelves 16 may be brushed from the upper to the lower shelves to accumulate 15 on the lowermost shelf in which this opening is formed. A suitable receptacle may then be placed beneath this opening and after removing the lid 21, the accumulated 20 sweepings may be brushed through the opening into such a receptacle. This provides, therefore, a convenient means for cleaning the case and disposing of the accumulated dirt.

25 Mounted above each shelf 16 and adjacent the rear thereof is a bar 22 running lengthwise of the case and mounted or supported on the ends thereof. This bar is formed with a series of notches 23 and has 30 mounted thereon at intervals therealong a series of clips 25. The clips 25 are fixed to the bar 22 by screws or other suitable means and are let into the surface thereof to a depth equal to that of the notch 23, so that 35 the front of the clip will be flush with the front surface of the bar. These clips are for the purpose of supporting the boxes of cigars arranged for display in the show case. Each box is mounted on a clip by forcing 40 the clip through the fabric forming the hinge of the box lid adjacent the middle of the lid and so that the clip passes to the inner side of the lid 26 of the box 27. When so mounted the edge of the lid 26 will rest 45 upon the shoulder 24 and the lid will be pressed against the bar 22 so as to support the box. It will be noted that since all of the boxes rest with their lids against the 50 notch 24, they will all be supported with their upper edges at the same level, regardless of the varying depths of the different boxes. The boxes will all be arranged, therefore, at a uniform level so as to present a neat and attractive appearance.

55 It will be seen, therefore, that this invention provides a show case which not only presents an attractive appearance, but which is easy to manipulate and arranged so as to promote effective salesmanship in dispensing the articles displayed. An attendant standing in rear of the case is in the best position to engage the customer in suitable conversation to promote the sale of the articles which the customer has on view directly 60 before him. The attendant can from his po-

sition easily and quickly manipulate the doors so as to open the case at either side according to the requirements of the customer. The salesman may either permit the customer to make his own selection from the case or he may by reaching over the narrow top take the articles from the case and present them to the customer. The interior of the case is arranged so that the display of cigars may be arranged attractively and in 75 neat order, all the boxes being arranged at a uniform level in each tier. Proper humidification is also provided. The arrangements for cleaning are adapted to permit the cleaning operation to be carried on rapidly and 80 conveniently and permit the disposal of the dirt in a simple and sanitary manner. The construction is simple in the extreme and, therefore, economical to manufacture so that the case may be sold at a low price. 85

It is obvious that various changes may be made in details of construction without departing from the spirit of this invention; it is, therefore, to be understood that this invention is not to be limited to the specific 90 details shown and described.

Having thus described the invention, what is claimed is:

1. In a show case, a horizontally movable door adapted to open or close the front of the case, a handle rigidly connected to the door and projecting outside of the case at the rear thereof adapted to operate the door.

2. In a show case, a horizontally movable door adapted to open or close the front of the case, and a handle rigidly attached to said door and projecting through the rear wall of the case for operating said door.

3. In a show case, a series of horizontally movable doors adapted to move past each other to open or close the front of the case and handles directly attached to said doors and extending to the rear wall of said case.

4. In a show case, a series of horizontally movable doors adapted to move past each other to open or close the front of the case, and handles fixed to said doors and projecting from the rear of the case.

5. In a show case, a series of horizontally movable doors adapted to move past each other to open or close the front of the case, and handles directly attached to said doors projecting from the rear of the case and adapted to pass each other during operation of the doors.

6. In a show case, a series of horizontally movable doors adapted to move past each other to open or close the front of the case, and handles directly attached to said doors projecting through slots in the rear wall of the case.

7. In a show case, a series of horizontally movable doors adapted to move past each other to open or close the front of the case, and handles rigidly attached to said doors

projecting through slots in the rear wall of the case, said handles being positioned one above another.

8. In a show case, a series of horizontally movable doors adapted to move past each other to open or close the front of the case, and handles on said doors and projecting through and movable in separate slots in the rear wall of the case.
- 10 9. A show case having a horizontally movable door sloping upwardly to the rear and terminating adjacent a narrow top, and a handle rigidly attached on said door projecting through and operable from the rear of the case.

10. In a show case having a series of horizontally movable doors sloping upwardly to the rear and terminating adjacent a narrow top, and handles rigidly attached on said doors projecting through and operable from the rear of the case.

11. In a show case having a top and a front, horizontally sliding door adapted to open or close the front of the case, and a handle rigidly secured to the upper part of said door and extending to the rear wall of said case.

In testimony whereof I affix my signature this 17th day of April, 1924.

CHARLES J. ABELN.
